HAIR CURLER

Felix Kapelman, Bronx, N. Y., assignor to Belta Comb Company, Inc., New York, N. Y., a corporation of New York

Application June 29, 1939, Serial No. 281,761

3 Claims. (Cl. 132—35)

This invention relates to improvements in hair curling devices and has particular reference to a combination comb and curler.

An object of the invention is to provide an improved device of simple and practical construction wherein a member is utilized, in combination with a comb, as a mandrel upon which a curl is formed.

Another object is to employ a member which forms a housing for a comb and is associated therewith in such manner that said elements will have relative movements that will permit the comb to be recessed within the housing and projected therefrom to a position wherein the comb will cooperate with the housing in the formation of a curl.

The above and other objects will appear more clearly from the following detailed description when taken in connection with the accompanying drawing which illustrates a preferred embodiment of the inventive idea.

Figure 1 is a side elevation of the curler device, with the comb housing in one position of adjustment wherein the comb employed in conjunction with the housing is recessed therein.

Figure 2 is a similar view with the housing adjusted so that a portion of the comb will be projected therefrom into cooperative relation with the housing to constitute a mandrel about which a strand of hair is curled.

Figure 3 is a top plan view of the device in the position of Figure 2.

Figure 4 is a section on the line 4—4 of Figure 2.

Figure 5 is a section on the line 5—5 of Figure 2, and

Figures 6 and 7 are views similar to Figure 5 showing the progressive steps in the formation of a curl.

Referring more particularly to the accompanying drawing, the numeral 8 indicates an ordinary comb from one end of the back of which there extends a rod generally indicated by the numeral 9. The inner portion 10 of said rod adjacent the comb back is circular in cross section while the outer portion 11 is flat with the exception of the reduced extremity 12 thereof. Said portion 11 is provided on opposed edges thereof with rows of comb teeth 13 for a purpose which will later appear.

Associated with the rod 9 is a member 14 of substantially semi-circular cross section. This member performs the three-fold function of providing a handle for the large comb, a housing for the small comb 13 and a mandrel about which

a curl is formed. The member or housing 14 includes the end walls 15 and 16 and an intermediate wall 17, said walls 15 and 17 having a bearing on the portion 10 of the rod 9 which extends therethrough and the end wall 16 likewise having a bearing on the reduced extension 12 of said rod. The intermediate wall 17 divides the housing into two compartments 18 and 19, the latter of which is adapted to receive the portion 11 of the rod and the teeth 13 which constitute the small comb which cooperates with the housing 14 in the formation of a curl. By so mounting the member 14 on the rod, the two elements are capable of relative rotary movements and the member 14, being slightly shorter than the rod 9 is also capable of longitudinal movements relative thereto. The portion of the partition 17 surrounding the opening through which the rod 9 extends is provided with a series of four notches 20 equi-distant about said opening and any one of these notches is adapted to receive a detent 21 formed on an adjacent portion of the rod 9 and as a lateral extension of one of the end teeth 13. When said detent is engaged in any one of the said notches, relative rotary movements between the rod 9 and the housing 14 are prevented. The detent 21 is yieldably held in a notch 20 by means of a spring 22 coiled about the circular portion 10 of said rod 9 and interposed between the partition 17 and a pin 23 which extends transversely through the portion 10 and abuts the end wall 15 of the housing. Said end wall 15 is spaced slightly from the adjacent end of the comb body 8 so as to permit a sufficient longitudinal movement of the housing 14 along the rod 9 and toward said comb 8 to permit the withdrawal of the detent 21 from the engaged notch, said movement being against the tension of the spring 22. When the detent is so withdrawn, a relative movement between the housing 14 and rod 9 may be effected whereby said housing may be adjusted from the position of Figure 1 to that of Figure 2, or vice versa. After being adjusted from one position to another, the detent 21 is again aligned with one of the notches 20 and a release of pressure upon the housing 14 will permit the spring 22 to force said housing outwardly upon the rod 9, and thereupon engage said detent in the aligned notch to releasably retain the housing in its adjusted position.

In the position of Figure 1, the comb 13 is in inoperative position wherein it is recessed within the compartment 19, as is illustrated in Figure 7, and the housing 14 may then be employed as a

handle for manipulating the large comb 8. When it is desired to form a curl, a relative movement between the housing 14 and rod 9 is effected as above described, and said housing may be adjusted to the position of Figures 2, 4, 5 and 6 in which one of the series of comb teeth 13 is projected laterally through the open side of the housing 14. The operator may then employ the projecting teeth 13, as in Figure 5, to initially 10 comb out a strand of hair 24 and, after this has been done, said strand may be wound about the housing 14 and the comb teeth 13, as shown in Figure 6. With the curl thus formed about said elements, which then combine to constitute a 15 mandrel, the comb 13 is then restored to the position of Figures 1 and 7 to free the teeth of the comb from the strand, after which the curl may be slipped off from the housing 14 to complete the operation.

20 What is claimed is:

1. In a hair curler, a rod having comb teeth thereon, a housing of semi-circular formation in cross section and having a bearing on said rod for providing relative rotary adjustments between 25 said parts, said housing having an open side through which said teeth project in one position of adjustment and which receive said teeth therein in another position of adjustment, spaced notches formed in a wall of said housing, and a 30 detent on said rod movable into said notches to releasably retain said teeth in their different positions of adjustment.

2. In a hair curler, a rod having comb teeth thereon, a housing through which said rod extends, there being relative rotary and longitudinal movements between said rod and housing and the teeth on said rod combining with said housing to form a mandrel about which a curl is formed when a relative rotary movement is effected to project said teeth from said housing, said teeth being also movable into a recessed position within said housing, notches formed in a wall of said housing, and a detent on said rod movable into said notches during a relative longitudinal movement between said rod and housing to releasably retain said teeth in their projected and recessed positions. 10

3. In a hair curler, a rod having comb teeth thereon, a housing having an open side and an intermediate wall through which said rod extends, there being relative rotary and longitudinal movements between said housing and rod and said teeth being projected from said open side and recessed within said housing during said rotary movements, notches formed in said intermediate wall, a detent on said rod movable into and out of said notches when relative longitudinal movements between said housing and rod are effected, and a spring for yieldably maintaining said detent within any one of said notches. 15 20 25
